UNITED STATES PATENT OFFICE.

DANIEL A. A. BUCK, OF WATERBURY, CONNECTICUT, ASSIGNOR TO THE
WATERBURY WATCH COMPANY, OF SAME PLACE.

MAINSPRING-BARREL FOR WATCHES.

SPECIFICATION forming part of Letters Patent No. 293,142, dated February 5, 1884.

Application filed July 21, 1883. (Model.)

To all whom it may concern:

Be it known that I, DANIEL A. A. BUCK, of Waterbury, in the county of New Haven, and in the State of Connecticut, have invented certain new and useful Improvements in Mainspring-Barrels for Watches; and I do hereby declare that the following is a full, clear, and exact description thereof, reference being had to the accompanying drawings, making a part 10 of this specification, in which—

Figure 1 is a perspective view of my spring-barrel and main wheel separated from each other. Fig. 2 is a like view of the same combined for use. Fig. 3 is a plan view of a watch-movement containing said parts. Fig. 4 is a section of the same upon line *xx* of Fig. 3.

Letters of like name and kind refer to like parts in each of the figures.

The design of my invention is to prevent injury to the train of a watch from breakage of the mainspring; and to this end it consists, in combination with stem-winding mechanism, in a mainspring-barrel made separate from the main wheel, journaled upon the main-wheel arbor, and provided with peripheral teeth, whereby it may be rotated upon and around said arbor to wind the mainspring, substantially as and for the purpose herein-after specified.

In the annexed drawings, A represents a mainspring-barrel, which has preferably somewhat less than the usual depth, and is provided upon its periphery with gear-teeth *a* of ordinary form. Said barrel is journaled upon the arbor *b* of the main wheel B, and its open end is contained within a recess, *b'*, which is provided within the contiguous face of said wheel, which latter acts as a cover for said barrel to confine the spring in place within the same.

The parts described being placed in position within the movement of a watch with the inner end of the mainspring attached to the arbor *b*, and the outer end of the same to the inner periphery of the barrel A, a spring-stop is provided for engagement with the teeth *a* of said barrel, and a winding-pinion, C, caused to mesh with the same, when said pinion will be revolved and said barrel rotated until said spring is wound, and its power, acting through the main wheel B, will actuate the train in the usual manner. If, now, the mainspring should break and expand in the ordinary manner against the inner periphery of the barrel, no damage could result to any portion of the train or to said barrel, for the reason that the latter would then be disconnected and free to revolve upon the arbor *b* without influence upon contiguous parts.

Having thus fully set forth the nature and merits of my invention, what I claim as new is—

In combination with stem-winding mechanism, a mainspring-barrel made separate from the main wheel, journaled upon the main-wheel arbor, and provided with peripheral teeth, whereby it may be rotated upon and around said arbor to wind the mainspring, substantially as and for the purpose specified.

In testimony that I claim the foregoing I have hereunto set my hand this 17th day of May, A. D. 1883.

DANIEL A. A. BUCK.
